CLAIM

The ornamental design for a sandal as shown and described.

DESCRIPTION

1.1 : Perspective

1.2 : Front

1.3 : Back

1.4 : Right

1.5 : Left

1.6 : Top

1.7 : Bottom

The characteristic features of the design reside in the shape of the sandal as shown; the reproductions of the design show a right shoe, the corresponding left shoe being a mirror image of the one shown in the reproductions.

1 Claim, 7 Drawing Sheets
